(57) **ABSTRACT**

A blow molded, hollow plastic container including two opposed, relatively longer sidewall portions which alternate with two opposed, relatively shorter sidewall portions. A first of the relatively shorter sidewall portions includes a grip area, and the opposed second relatively shorter sidewall portion includes a pour area.

PLASTIC CONTAINER INCLUDING A GRIP FEATURE

CROSS-REFERENCE TO RELATED APPLICATIONS

This application is a continuation-in-part of U.S. patent application Ser. No. 29/217,522, filed Nov. 18, 2004 now U.S. Pat. No. D, 530,617.

BACKGROUND OF THE INVENTION

Plastic containers are widely used commercially for a variety of products. It is highly desirable to provide a plastic container which facilitates ease of product dispensing, while at the same time providing a container with an improved configuration which enables more convenient handling in the product preparation and filling cycles and by the consumer in use. It would also be advantageous to provide a light weight container which would enable rapid cycle times in the container preparation and filling procedure while facilitating product use, especially product dispensing from the container.

It is, therefore, an object of the present invention to provide an improved plastic container which facilitates product dispensing and which enables ease of use by the consumer.

It is a further object of the present invention to provide an improved plastic container as aforesaid with an improved container configuration which enables convenient handling in the product preparation and filling cycles and by the consumer in use.

Further objects of the present invention will appear hereinbelow.

SUMMARY OF THE PRESENT INVENTION

In accordance with the present invention the foregoing objects and advantages are readily obtained.

The improved plastic container of the present invention comprises: a blow molded, hollow plastic container having a generally oval base, a cylindrical sidewall extending upwardly from the base, and a neck finish extending upwardly from the sidewall and having a generally oval opening to the inside of the container; wherein said container includes two opposed, relatively longer sidewall portions which alternate with two opposed, relatively shorter sidewall portions; and with a first of said relatively shorter sidewall portions being relatively longer than a second of said relatively shorter sidewall portions, and with said first relatively shorter sidewall portions including an integral grip area thereon, as a hand or finger grip area.

The neck finish of said container advantageously includes two opposed, relatively longer side portions which extend upwardly from said longer sidewall portions and two opposed, relatively shorter side portions which extend upwardly from said shorter sidewall portions. A first of said relatively shorter neck finish side portions is desirably relatively longer than a second of said relatively shorter neck finish side portions and extends upwardly from said first relatively shorter sidewall portions.

Preferably, the circumference of the oval opening is smaller than the circumference of the oval base. Preferably also the grip area extends over a portion of said relatively longer sidewall portions, and said second relatively shorter sidewall portion includes a recessed pour area beneath the second of said relatively shorter neck finish side portions.

While the plastic container can be readily used with any plastic material, it is particularly suitable for use with polyethylene terephthalate.

Further features and advantages of the present invention will appear hereinbelow.

BRIEF DESCRIPTION OF THE DRAWINGS

The present invention will be more readily understandable 10 from a consideration of the following illustrative drawings, wherein:

FIG. 1 is a right side view of one embodiment of the plastic container of the present invention;

FIG. 2 is a front elevational view thereof;

FIG. 3 is a rear elevational view thereof;

FIG. 4 is a top plan view thereof;

FIG. 5 is a bottom plan view thereof;

FIG. 6 is a perspective view thereof showing the front, right side and top thereof; and

FIG. 7 is a left side view thereof.

DETAILED DESCRIPTION OF PREFERRED EMBODIMENTS

Referring to the drawings, FIGS. 1-7 show one embodiment of the plastic container of the present invention.

FIG. 1 shows plastic container 10 of the present invention with container portion 12 and integral grip area 14. The container is a hollow, blow molded plastic container having a lower supporting base 16, a sidewall 18 extending upwardly from the base, and a neck finish 20 extending upwardly from the sidewall and having an opening 22 to the inside of the container. As can be clearly seen in FIGS. 4-6, the plastic container 10 has a generally oval base 16 and a generally oval opening 22 to the inside of the container.

The containers of the present invention are preferably made of a pliable, deformable, synthetic plastic material, such as for example, polyethylene, polypropylene, or polyethylene terephthalate (PET), or other plastic material, although PET is generally used.

The particular neck portion 22 shown in the embodiment of FIGS. 1-7 includes an upper flange portion 24 for a snap-on closure and/or a foil closure (not shown). However, other type neck finishes can be readily employed, as a threaded section to accommodate a screw-on closure. Also, the outer extent of the upper neck finish in the embodiment shown extends inwardly of the sidewall, which is preferred.

Plastic container 10 includes two, opposed first and second relatively larger sidewall portions 26, 28, respectively, which alternate with two opposed, first and second relatively shorter sidewall portions 30, 32, respectively. The first relatively shorter sidewall portion 30 is relatively longer than the second of said relatively shorter sidewall portion 32. In addition, grip area 34 is included on the first relatively shorter sidewall portion 30. The grip area 34 is a hand or finger grip area which includes first and second spaced apart recessed areas 36 and 38, respectively, each of which extends onto the adjacent relatively longer sidewall portions. That is, first recessed area 36 extends onto first relatively longer sidewall portion 26 and second recessed area 38 extends onto second relatively longer sidewall portion 28. Thus, a convenient hand or finger grip area is provided which facilitates a strong and firm hold onto the container by the user.

Similarly, the neck finish area 20 includes two, opposed first and second relatively longer side portions 40, 42, respectively, which extend upwardly from the longer sidewall portions 26, 28, respectively, and two opposed first and second

relatively shorter side portions 44, 46, respectively, which extend upwardly from the shorter sidewall portions 30, 32, respectively. The first relatively shorter neck finish side portion 44 is relatively longer than the second relatively shorter neck finish side portion 46 to provide a convenient dispensing or pour channel at the shorter neck finish side portion 46. The dispensing function is enhanced by a recessed dispensing or pour area 48 beneath the second shorter neck finish side portion 46 on the second shorter sidewall portion 32. The dispensing function is further enhanced by providing that the circumference of the neck finish opening 22 is smaller than the circumference of the base 16. In addition, the corners of the second shorter neck finish side portions have a round circumference to further facilitate dispensing.

Thus, it can be seen that the plastic container of the present invention is extremely convenient for handling and dispensing contents. The grip area is opposed to the dispensing area and the sidewall and neck finish features make the container quite easy to use. An additional advantage of the present container is that the container is readily stackable.

It is to be understood that the invention is not limited to the illustrations described and shown herein, which are deemed to be merely illustrative of the best modes of carrying out the invention, and which are susceptible of modification of form, size, arrangement of parts and details of operation. The invention rather is intended to encompass all such modifications which are within its spirit and scope as defined by the claims.

What is claimed is:

1. A plastic container which comprises:

a blow molded plastic body having a generally rounded trapezoidal-shaped base, a generally rounded trapezoidal-shaped sidewall extending upwardly from the base, and a neck finish extending upwardly from the sidewall and having a generally rounded trapezoidal-shaped opening to a container interior; 35
wherein said sidewall includes two opposed, relatively longer sidewall portions which alternate with two opposed, relatively shorter sidewall portions; said neck finish includes two opposed relatively longer neck finish side portions which extend upwardly from said longer sidewall portions, and two opposed relatively shorter first and second neck finish side portions which extend upwardly from said shorter sidewall portions, the first relatively shorter neck finish side portion is relatively 40 longer than the second relatively shorter neck finish side portion; 45
a first of said relatively shorter sidewall portions being relatively longer than a second of said relatively shorter sidewall portions, with said first relatively shorter sidewall portion including:
a height extending between the base and the neck finish, and
an integral hand or finger grip area including two spaced apart grip area recesses extending a vertical distance 50 that is greater than one-half of the height of the first relatively shorter sidewall portion, and a first of said grip area recesses extends over a portion of a first of said longer sidewall portions that is adjacent to the first grip area recess; and,
wherein a first circumference of the opening is smaller than a second circumference of the base, and a total length of the first longer sidewall portion is greater than the height of the first relatively shorter sidewall portion.
2. The plastic container according to claim 1, wherein an outer extent of the neck finish extends inwardly of the sidewall.

3. The plastic container according to claim 1, wherein the neck finish includes a flange portion for a snap-on closure.

4. The plastic container according to claim 1, for holding and dispensing contents.

5. The plastic container according to claim 1, wherein the plastic container is a single one-piece, unitary molded container.

6. The plastic container according to claim 1, wherein the two opposed relatively longer sidewall portions are generally angled with respect to one another.

7. The plastic container according to claim 1, wherein the two opposed relatively longer neck finish side portions are generally angled with respect to one another.

8. The plastic container according to claim 1, wherein a first perimeter of the opening is similarly shaped to a second perimeter of the sidewall.

9. The plastic container according to claim 1, wherein a first outer edge of the relatively shorter second neck finish side portion outwardly extends a first distance and a second outer edge of the shorter sidewall portion provided vertically below the relatively shorter second neck finish side portion outwardly extends a second distance, wherein the first distance is substantially equal to the second distance.

10. A single one-piece, unitary molded plastic container comprising:

a generally rounded trapezoidal-shaped base;
a generally rounded trapezoidal-shaped sidewall extending upwardly from the base; and,
a neck finish extending upwardly from the sidewall and having a generally rounded trapezoidal-shaped opening to a container interior;

wherein the sidewall includes two opposed, relatively longer sidewall portions which alternate with two opposed, relatively shorter sidewall portions; the neck finish includes two opposed relatively longer neck finish side portions which extend upwardly from the longer sidewall portions, and two opposed relatively shorter first and second neck finish side portions which extend upwardly from the shorter sidewall portions, the first relatively shorter neck finish side portion is relatively longer than the second relatively shorter neck finish side portion; and

a first of said relatively shorter sidewall portions being relatively longer than a second of said relatively shorter sidewall portions, with said first relatively shorter sidewall portion including:

a height extending between the base and the neck finish, and
an integral hand or finger grip area including two spaced apart grip area recesses extending a vertical distance that is greater than one-half of the height of the first relatively shorter sidewall portion, and a first of said grip area recesses extends over a portion of a first of said longer sidewall portions that is adjacent to the first grip area recess; and,

wherein a first circumference of the opening is smaller than a second circumference of the base, and a total length of the first longer sidewall portion is greater than the height of the first relatively shorter sidewall portion.

11. The single one-piece, unitary molded plastic container according to claim 10, wherein the two opposed relatively longer sidewall portions are generally angled with respect to one another; and the two opposed relatively longer neck finish side portions are generally angled with respect to one another.

12. The single one-piece, unitary molded plastic container according to claim 10, wherein the opening and the sidewall have perimeters that are similar in shape.

5

13. A single one-piece, unitary molded plastic container comprising:

- a generally rounded trapezoidal-shaped base;
- a generally rounded trapezoidal-shaped sidewall extending upwardly from the base; and
- a neck finish extending upwardly from the sidewall and having a generally rounded trapezoidal-shaped opening to a container interior;

wherein the sidewall includes two opposed, relatively longer sidewall portions which alternate with two opposed, relatively shorter sidewall portions; the neck finish includes two opposed relatively longer neck finish side portions which extend upwardly from the longer sidewall portions, and two opposed relatively shorter first and second neck finish side portions which extend upwardly from the shorter sidewall portions, the first relatively shorter neck finish side portions is relatively longer than the second relatively shorter neck finish side portion;

wherein a first of the relatively shorter sidewall portions is relatively longer than a second of the relatively shorter sidewall portions, the first relatively shorter sidewall portion includes:

an integral hand or finger grip area, the grip area extends over a portion of the relatively longer sidewall portions, the grip area includes two spaced apart recess grip areas that each extend over a portion of the adjacent longer sidewall portions;

5

10

15

20

25

6

wherein the second relatively shorter sidewall portion includes:

- a height extending between the base and the neck finish, and

- a pour area recess beneath the second relatively shorter neck finish side portion,

wherein the pour area recess longitudinally extends along a majority of the height of the second relatively shorter sidewall portion; and,

wherein a total length of a first of said longer sidewall portions is greater than the height of the second relatively shorter sidewall portion.

14. The single one-piece, unitary molded plastic container according to claim 13, wherein the second relatively shorter sidewall portion includes a recessed pour area beneath the second relatively shorter neck finish side portion.

15. The single one-piece, unitary molded plastic container according to claim 13, wherein the integral hand or finger grip area extends a distance in the upward direction that is greater than one-half the total vertical height of the container.

16. The single one-piece, unitary molded plastic container according to claim 13, wherein an outer edge of the relatively shorter second neck finish side portion extends substantially to the same outward extent as an outer edge of the shorter sidewall portion provided vertically below the relatively shorter second neck finish side portion.
